UNITED STATES PATENT OFFICE.

LOUIS E. WALKINS, OF SPRINGFIELD, MASSACHUSETTS.

ELECTRIC-RAILWAY SYSTEM.

SPECIFICATION forming part of Letters Patent No. 656,276, dated August 21, 1900.

Application filed December 15, 1898. Serial No. 699,401. (No model.)

To all whom it may concern:

Be it known that I, LOUIS E. WALKINS, a citizen of the United States of America, and a resident of Springfield, in the county of 5 Hampden and State of Massachusetts, have invented certain new and useful Improvements in Electric-Railway Systems, of which the following is a full, clear, and exact description.

This invention relates to improvements in 10 electric-railway systems of the third-rail sectional-conductor class, the object being to provide simple and operative devices for automatically cutting in and cutting out the current from the third-rail blocks or sections 15 as the car having the electric motor thereon passes thereover.

The invention consists in the combination or arrangement of parts and in the construction of certain of the parts, all substantially 20 as will hereinafter fully appear, and be set forth in the claims.

Reference is to be had to the accompanying drawings, in which—

Figure 1 is a plan view of the electric rail-way arranged in accordance with this invention. Fig. 2 is a cross-sectional view and elevation of parts in detail, to be hereinafter referred to. Fig. 3 is a cross-sectional view, on a larger scale, as taken substantially on 25 the line 3 3, Fig. 1, showing the action of a broad-tread car-wheel for downwardly moving a depressible member of the device adjacent the track-rail. Line 2 2 on Fig. 3 indicates the plane on which the parts in section 30 in Fig. 2 are drawn. Fig. 4 is a view similar to Fig. 3, but showing the relations of the parts before the depressible member is forced down.

Similar characters of reference indicate 40 corresponding parts in all of the views.

In the drawings, A A represent the usual track-rails of a railway, outside of, near, and parallel with one of which are the series of third-rail sections or blocks B B, the length 45 of each of which may be as desired—for instance, an eighth or a quarter of a mile.

C represents the dynamo, understood as located in a power-station and having connected therewith the wire a, which is also 50 connected with the feed or line wire D for the system, and with the continuous return-

wire E for the system the wire b is connected, which returns to the generator, all as usual, and one or both of the track-rails at suitable intervals is by the conductor d connected 55 with the return-wire.

Provided for each third-rail section B are devices as follows: G represents an electro-magnet understood as wound with heavy wire, with each of which a branch or sub-wire f 60 from the feed-wire is connected. g represents a lever intermediately pivoted at 10 below the electromagnet, one arm thereof being constructed to constitute, or being provided with, an armature h to coact with and 65 to be drawn to the electromagnet when the latter is vitalized and to be held thereagainst while it remains vitalized. Said armature-carrying extremity of the lever is provided with the counterpoise-weight 12. The opposite member 13 of the lever g is by the link 14 connected with the depressible and vertically-guided part H, having its position very close to the side of the car-wheel rail A and normally standing above the top or tread of such rail. 70 The upper edge of this depression member is crowning or rounded, as shown in Fig. 2. The lever is provided with the upwardly-extending switch-arm i, projecting radially from the pivot 10 and adapted to be moved onto and 75 out from contact with the metallic contact-piece j, having a fixed support adjacent the said arm i, and from this contact j an electric wire m connects with the third-rail section B, corresponding to the device comprising the 80 contact j and the switch-arm i, in conjunction with the electromagnet and lever. An electric wire n is connected with the coil of electromagnet at the opposite end thereof from that at which the wire f is understood as having 85 connection. These parts described are inclosed in a suitable cast-iron box or case J, one design of which is shown in Figs. 3 and 4, but which may be variable in size and form, still having fitness to purpose. 90

One of the car-wheels of the motor-car or train run over this railway is to have a tread wider than the tread of the track-rail, so as to extend over and depress the aforesaid part H when such wheel comes to the location 95 thereof. (See Fig. 3.)

A shoe or depending trolley L is understood

as being carried by the electric car to run on the third-rail sections, the same having a conductor *o* extending therefrom to the car-motor *M*, while from the motor a suitable conductor (indicated at *p*) connects with the car-wheel axle.

In operation so soon as the wheel of the car reaches the third-rail section at which the devices described comprising the depressible member *H* are located such member *H* will be depressed, throwing the armature against the electromagnet *G* and placing the switch-arm *i* on the contact *j*, whereby the feed-current will pass from the feed-wire *D* through the electromagnet, conductor *n*, switch-arm *i*, and conductor *m* to the third-rail section next and corresponding to the said devices, giving the power-current into such third-rail section, to be taken up through the shoe to the motor and back through the track-rail and cross-conductor *d* to the continuous return-wire *E*, it being understood that these relations of the movable parts are retained so long as the motor-car remains on this given section, because while it so remains on the section there is a complete circuit, as stated, which maintains the electromagnet live holding the armature thereagainst and keeping the switch-arm *i* on the contact *j*; but so soon as the car passes off this section onto the next third-rail section, the one being understood as insulated from the other, the aforementioned conditions for the maintenance of the circuit are discontinued in the first-named third-rail section; but such conditions are next created for the succeeding third-rail section.

I claim for this apparatus simplicity of construction with corresponding cheapness, operativeness, and accessibility for repairs or replacement of parts.

Having thus described my invention, what I claim, and desire to secure by Letters Patent, is—

45 1. In an electric-railway system, the combination with the usual track-rails and a series of successive third-rail sections, and a continuous current-feed wire, of devices for each third-rail section each consisting of an electromagnet, a depressible member movably mounted adjacent the magnet and having its top normally above the tread of one of the track-rails, a lever adapted to be swung

in conjunction with the movements of said depressible member and having an armature 55 coacting with the electromagnet, a contact-piece, electrically connected with the third-rail section, a switch member constituted by a member of said lever and adapted to make and break connection with said contact-piece, 60 a conductor connecting the feed-wire with the coil of the electromagnet and a conductor also connecting the coil of the electromagnet with said switch member, substantially as and for the purpose set forth. 65

2. In an electric-railway system, the combination with the usual track-rails *A A* and a series of successive third-rail sections and a continuous current-feed wire, of devices for each third-rail section, each consisting of 70 an electromagnet, a depressible member *H* movably mounted adjacent the magnet and having its top normally above the tread of one of the track-rails, an intermediately-pivoted lever, one arm of which is connected with said depressible member, the other arm extending adjacent the electromagnet and having an armature and a counterpoise-weight, the switch-arm *i* carried by said lever, and a stationary contact-piece *j* with which said 75 switch-arm passes to and out of contact in conjunction with the movement of the lever, a wire connecting the electromagnet and said feed-wire, another wire connecting the electromagnet and the switch-arm and a wire 80 connecting the contact-piece *j* and the third-rail section, substantially as described.

3. An electric current switching and maintaining device, for electric-railway systems consisting of a vertically-guided normally- 90 elevated depressible member, the intermediately-pivoted lever *g* linked to said depressible member, and having an arm thereof provided with an armature, an electromagnet with which said armature coacts, the switch-arm *i* extending radially from the pivot of said lever, and movable with the latter, a wire connecting the electromagnet and said switch-arm, the contact *i* adjacent the switch-arm and the conductor *m* connected with said contact, substantially as described and shown. 95 100
